UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

SEAM FOR SEWED ARTICLES.

1,279,847.

Specification of Letters Patent. Patented Sept. 24, 1918.

Application filed January 2, 1917. Serial No. 140,123.

To all whom it may concern:

Be it known that I, ALBERT H. DE VOE, a citizen of the United States, residing at Westfield, in the county of Union and State 5 of New Jersey, have invented certain new and useful Improvements in Seams for Sewed Articles, of which the following is a specification, reference being had therein to the accompanying drawings.

10 This invention relates to seams for sewed articles and has for an object to provide a seam wherein upper and lower strips of material, such as tape, braid or the like, are secured together or to the top and bottom faces 15 of intermediate material by spaced rows of stitches disposed along the margins of said strips and so formed that the connecting thread-portions between adjacent penetrative thread-loop structures are hidden from 20 view.

More particularly, the invention has for an object to provide a seam wherein upper and lower tapes are connected together by marginally disposed rows of blind-stitches 25 which may pass through intermediate material.

A further object of the invention is to provide a seam wherein juxtaposed edge-portions of material are joined and covered 30 by upper and lower tapes connected together by marginally disposed rows of blind- 35 stitches passing through said juxtaposed edge-portions.

Further objects of the invention will appear from the following description and claims.

These objects are attained by the improved seam structure which, in its preferred embodiment, comprises body-fabric material

40 presenting juxtaposed edge-portions which are joined and covered by upper and lower tapes connected together by spaced rows of blind-stitches passing through said body-fabric material. Each row of stitches comprises a series of keyed, penetrative, thread-loop structures, each of which enters and emerges from the inner or hidden surfaces of said tapes, preferably without showing at the outer or visible surfaces thereof.

50 In the accompanying drawings, Figure 1 illustrates a convenient mechanism for carrying the invention into effect. Fig. 2 is a perspective view of an embodiment of the invention and Figs. 3 and 4 are sectional

views of modified seam-structures embodying the invention.

In the embodiment illustrated in Fig. 2, the seam comprises two juxtaposed edge-portions *a*, *b*, of material, arranged in overlapping relation and including the inwardly folded portions *c*, *d*, respectively. Upper and lower tapes 1 and 2, respectively, cover the juxtaposed edge-portions *a*, *b*, and are connected together by the spaced rows of 60 stitches 3, 3, formed within the marginal portions 4, 5, of said tapes and passing through the edge-portions *a*, *b*, of the intermediate material.

Each of the rows of stitches 3 comprises a series of keyed, penetrative thread-loop structures 6, each of which structures enters the inner or hidden surface of the upper tape 1 at the point 7, emerges from said surface at 8, passes downwardly through the juxtaposed edge-portions *a*, *b*, of the body-fabric, enters the inner or hidden surface of the lower tape 2 at 9 and emerges from said surface at 10. In the present instance adjacent thread-loop structures 6 are connected together by the thread portions 11, 11, which 70 extend along the inner or hidden surfaces of the tapes 1 and 2 and are therefore concealed.

In the modification of the invention illustrated in Fig. 3, the juxtaposed edge-portions *a'*, *b'*, are disposed in overlapping relation but the inwardly folded portions *c'*, *d'*, are also disposed in overlapping relation instead of in abutted relation, as are the corresponding portions shown in Fig. 2. Spaced 80 rows of the stitches 3, 3, serve to join the fabric portions *a'*, *b'*, and secure the covering tapes 1 and 2 in position.

In the modification of the invention illustrated in Fig. 4, the juxtaposed edge-portions *a''*, *b''* of material, are disposed in abutted relation in the same plane and are joined and covered by the tapes 1, 2 and connecting stitches 3, 3.

Although the above and other modifications of the invention may be produced independently of a machine, I have fully disclosed a convenient mechanism for forming seams of the present character in my co-pending application Serial No. 140,122 filed January 2, 1917. This mechanism comprises an upper tape-guiding frame in the form of a presser-foot 12 which is carried 100 105

- by the usual presser-bar 13. The sole-portion 14 of the presser-foot 12 is formed with a tape-inverting edge 15 arranged substantially at right angles to the line of feed. 5 As the work passes beneath the presser-foot the upper tape 1 is drawn forwardly through a suitable aperture 16 in the shank of the presser-foot and is inverted over the edge 15. The lower tape 2 is drawn forwardly through a passage-way 17 beneath the cloth-plate 18, through a guiding slot 19 in the usual four-motion feed-bar 20 and about the inverting edge 21 which forms the rear wall of a needle-receiving slot 22 10 cut in the auxiliary throat-plate 23. The lower inverting edge 21 is also disposed at substantially right angles to the line of feed and in the vertical plane of the upper inverting edge 15. 15 The stitch-forming mechanism comprises the reciprocating needle-bar 24 carrying a pair of eye-pointed needles 25, 25, which are disposed in a vertical plane at right angles to the line of feed and closely in front of 20 the plane of the inverting edges 15 and 21. 25 As the needles 25 descend they will split the bent portions of the tapes 1 and 2 which are presented by the inverting edges 15 and 21, respectively, and stitch said tapes together 30 or to the opposite faces of the intermediate body-fabric material indicated at *f* in Fig. 1.

In the present instance a two-thread lock-stitch example of keyed, penetrative, thread-loop structure is shown, the keying being accomplished by the interlocking of the upper and lower threads at the point 26. The invention is not limited, however, to the use of a lock-stitch. Furthermore, in the embodiments illustrated, the location of the locking point 26 is immaterial.

Having thus set forth the nature of the invention, what I claim herein is:—

1. A seam for sewed articles comprising upper and lower plies of material and spaced rows of blind fastening stitches connecting said plies, each of said rows of

stitches including a series of keyed, penetrative, thread-loop structures which enter and emerge from the inner or hidden surfaces of 50 said plies and are concealed at the outer or visible surfaces of said plies.

2. A seam for sewed articles comprising upper and lower tapes and spaced rows of blind fastening stitches connecting the marginal portions of said tapes, each of said rows of stitches including a series of keyed, penetrative thread-loop structures, each of said structures entering and emerging from the inner or hidden surfaces of said tapes 60 without showing at the outer or visible surfaces thereof.

3. A seam for sewed articles comprising juxtaposed marginal portions of material, upper and lower tapes covering said marginal portions, and spaced rows of blind fastening stitches connecting said tapes along their margins, each of said rows of stitches including a series of keyed, penetrative thread-loop structures each entering and 70 emerging from the inner or hidden surfaces of said tapes without showing at the outer or visible surfaces thereof and passing through the intermediate material.

4. A seam for sewed articles comprising, two pieces of material having edge-portions disposed in overlapping relation, and means for securing said edge-portions together, said means comprising upper and lower tapes extending along and covering the 80 overlapping edge-portions of material and spaced rows of blind fastening stitches connecting said tapes along their margins, each of said rows of stitches including a series of keyed penetrative thread-loop structures 85 each entering and emerging from the inner or hidden surfaces of said tapes without showing at the outer or visible surfaces thereof and passing through the intermediate edge-portions of material.

In testimony whereof, I have signed my name to this specification.

ALBERT H. DE VOE.
